Application October 14, 1932, Serial No. 637,844
In Great Britain October 20, 1931

3 Claims. (Cl. 23—277)

This invention relates to processes in which ammonia is decomposed with the object of producing a gas consisting substantially of nitrogen or of nitrogen containing a small amount of hydrogen. It is known that ammonia will decompose at an elevated temperature in the presence of a catalyst to yield a mixture of nitrogen and hydrogen and it has been proposed to prepare a gas containing nitrogen for use in metallurgical operations by burning this nitrogen-hydrogen mixture with air and subsequently separating the water formed from the residual nitrogen.

We have now found that a particularly suitable method for carrying out such a process consists in arranging for the heat generated in the combustion step to be returned to the cracking step, thus dispensing with the need of auxiliary heating.

The invention consists accordingly in the partial or complete decomposition of ammonia into its elements and the combustion with air of the completely or partially decomposed gas, the two reactions being performed in heat exchange with each other. The amount of air supplied for combustion may be varied according as the final gas is to consist substantially of nitrogen or is to contain small amounts of hydrogen.

A suitable apparatus for carrying out the invention consists in a cylindrical combustion chamber in one end of which is situated a coiled iron tube which acts as a decomposing or cracking chamber. Instead of an iron coil, a chamber filled with an ammonia decomposing catalyst may be used, such chamber being arranged in thermal contact with the products of combustion in the combustion space. Thus the catalyst chamber may be an annular space surrounding the combustion chamber. A supply of ammonia gas is admitted to the coil or catalyst space from a cylinder of anhydrous ammonia or other convenient source, and in starting up the apparatus heat is supplied by burning in the combustion chamber a coal gas or hydrogen flame, or a flame of ammonia burning in oxygen may be employed. An electric heater may also be employed if desired in starting up. When the coiled iron tube or catalyst space has been raised to a sufficiently high temperature, decomposition of the ammonia commences and the partially cracked gas is then admitted into the combustion chamber, together with the necessary amount of air. It is necessary that approximately 15 per cent of the ammonia should be cracked in order that combustion may occur and providing this limit has been attained in the initial start-up the heat developed

by combustion of the hydrogen is sufficient to maintain reaction between ammonia and the air and there is a net balance of heat which is transmitted to the cracking chamber, that is the coiled iron tube or catalyst space. An equilibrium temperature will ultimately be set up and depending on the particular form of apparatus and the efficiency of the thermal insulation present, the degree of cracking will vary. The final products, however, are independent of the degree of cracking and are treated for the removal of water and the production of a substantially pure nitrogen gas in any suitable manner. When equilibrium has been attained it is necessary to adjust the air supply in order that no ammonia appears in the products of combustion. Excess of air should be avoided as it leads to the presence of free oxygen in the final gas, and the air supply to the combustion chamber is suitably controlled by making test analyses from time to time of the issuing gases.

In addition to the production of pure nitrogen, the apparatus described is particularly suitable for the economical production of gases containing up to about 10 per cent. hydrogen, the remainder being substantially pure nitrogen. The economic production of such a gas is important for purposes such as bright annealing of metals, particularly non-ferrous metals. In certain circumstances the presence of even small amounts of oxygen in annealing furnace atmospheres is highly undesirable but by the production of a gas containing hydrogen as described above, no free oxygen is possible in the products of combustion delivered from the apparatus. In order to produce hydrogen-nitrogen mixtures it is only necessary to vary the proportion of air which is introduced into the combustion space of the apparatus, the ratio of air to ammonia being reduced according to the percentage of hydrogen which is required in the final gas mixture.

An apparatus answering to the above description is illustrated in the accompanying drawing, which is a sectional elevation. In this drawing, the combustion chamber consists of two cylinders 1 and 2, fixed end to end by bolted flanges 3 and 4. The top cover 5 of the chamber is bolted to flanges on the cylinder 1 and has a central outlet 6 for the combustion products, which are led away by a branch pipe 7. Ammonia is introduced by pipe 8, which passes through the cover 5 and is then developed into a coil 9 terminating in an outlet pipe 10 which passes through the cover 5 and is connected to an external pipe 11 which leads the cracked gas to the lower end of the 55

combustion chamber and terminates in the bottom cover 12. The cover 12 is provided with air ports 13 and a rotary perforated plate 14 which controls the air supply. The cylinder 2 is lined 5 internally with refractory material 15 to protect the walls from the initially very hot gases, and the lining is bevelled as shown so as to allow of the entrance of air through the ports 13. The gases pass upwardly into the space enclosed by 10 the coil 9, which is closed at the top by a plate 16, and owing to the tapered form of the coil fractions of the gas are successively by-passed through the coil towards the walls of the cylinder, thus ensuring as far as possible that each turn of 15 the coil is swept by the gases. For this purpose the external diameter of the turn of the coil first encountered by the combustion gases approximates to that of the internal diameter of the cylinder 1, as shown in the drawing.

20 I claim:—

1. An apparatus for the decomposition of ammonia into its elements and for the combustion with air of the resulting gases, comprising a cylindrical combustion chamber, a coiled iron tube 25 located in one end thereof and adapted to be swept externally by the combustion products, means for admitting ammonia to said coil and for withdrawing the decomposition products therefrom, means for passing the said decomposition

products to the other end of the combustion chamber, and means for admitting air into said combustion chamber in amounts controllable with respect to the rate of flow of said gases.

2. An apparatus as set forth in claim 1, in 5 which the coil is co-axial with the combustion chamber and the turn of the coil first encountered by the combustion products is in contact with the wall of the combustion chamber, while the succeeding turns of the coil are spaced progressive- 10 ly further apart from said wall.

3. An apparatus for the decomposition of ammonia into its elements and further combustion with air of the resulting gases, comprising two 15 separably connected cylinders placed end to end, the first of said cylinders containing a coiled cracking tube adapted to be traversed internally by the ammonia to be decomposed and to be swept externally by the gaseous products resulting from the combustion of the decomposed gas, 20 and the second of said cylinders having an internal lining, of refractory material, means for introducing the decomposed gas together with air into the end of the second cylinder remote from the first cylinder, and means for withdrawing the 25 combustion products from the remote end of the first cylinder.

ERIC HALL SALISBURY.
